(57) **CLAIM**

The ornamental design for a cabinet, as shown and described.

DESCRIPTION

FIG. 1 is a front, right, upper perspective view of a first embodiment of a cabinet embodying our new design;

FIG. 2 is a front elevational view thereof;

FIG. 3 is a top plan view thereof;

FIG. 4 is a right side elevational view thereof, the left side elevational view being a mirror image thereof;

FIG. 5 is a rear elevational view thereof;

FIG. 6 is a bottom view thereof;

FIG. 7 is a front, right, upper perspective view of a second embodiment of a cabinet embodying our new design, the top plan view being identical to the view shown in FIG. 3; the right side elevational view being identical to the view shown in FIG. 4, the left side elevational view being a mirror image of the view shown in FIG. 4, the rear elevational view being identical to the view shown in FIG. 5; the bottom view being identical to the view shown in FIG. 6; and,

FIG. 8 is a front elevational view thereof.

The broken line representations of support legs in FIGS. 1-2 and 4-8, of a drawer pull in FIGS. 1-4 and 6-8, and of shelving in FIGS. 1-2 are for the purposes of illustration only, and form no part of the claimed design. The broken away portions shown in FIGS. 1-3 and 5-8 represent indeterminate width of the claimed design.
